UNITED STATES PATENT OFFICE.

WALLACE I. STIMPSON AND HARRY A. DAVIS, OF HOPEDALE, MASSACHUSETTS, AS
SIGNORS TO DRAPER CORPORATION, OF HOPEDALE, MASSACHUSETTS, A COR-
PORATION OF MAINE.

AUTOMATICALLY FILLING REPLENISHING SHUTTLE FOR LOOMS.

Application filed October 6, 1925. Serial No. 60,724.

To all whom it may concern:

Be it known that we, WALLACE I. STIMPSON and HARRY A. DAVIS, citizens of the United States, residing at Hopedale, in the 5 county of Worcester and State of Massachusetts, have invented an Improvement in Automatically Filling Replenishing Shuttles for Looms, of which the following description, in connection with the accompanying 10 drawings, is a specification, like characters on the drawings representing like parts.

This invention relates to automatically filling replenishing shuttles for looms and more particularly to the bobbin holding end 15 of such shuttles.

It is now the ordinary practice in shuttles of this general type to provide spring jaws for engaging the head end of the bobbin, and owing to the distribution of the spring 20 action, the jaws frequently break towards the bobbin holding portion thereof. In such prior constructions, also, it has been usual to provide the jaws by bending a piece of metal into loop form and securing 25 it by a cross-bolt in the shuttle, but such loop form of jaws as heretofore made has not been constructed with due regard to the strains placed upon the jaws during replenishment, with the result that in many cases 30 the jaws themselves break or they become loosened with respect to the shuttle itself.

One of the objects of the present invention is to provide a filling replenishing shuttle with bobbin holding jaws and shank 35 portion of equal vertical width throughout, and to provide between the shank and the bobbin holding jaws bow portions which are weakened or recessed in order to distribute the spring action of the jaws and 40 confine it to the bow portion connecting the bows with the shank, the result being that when the jaws are forced apart by the incoming filling carrier or bobbin, the bow portions only of the jaws will be subjected 45 to resiliency or spring action.

When the jaws are suddenly spread apart by the incoming filling carrier or bobbin, and the spring of the jaws is confined to the bow portion, as contemplated by the present 50 invention, there results a strain or compression upon the wood of the shuttle where the bow portion of the bobbin holder merges into the shank, and another feature of the present invention therefore consists in re-

inforcing the walls of the shank receiving 55 chamber formed in the wood of the shuttle, to thereby prevent injury to the wood of the shuttle. Another feature of the invention in these respects is that the wood of the shuttle is provided with an elongated shank 60 receiving chamber and the shank of the bobbin holder is likewise elongated to receive a through-bolt which unites the metal portions of the bobbin holder and associated 65 parts together as a unit, a cross-bolt, as usual, being employed for assisting in maintaining the parts in their working relations.

Since the bobbin holding jaws are subject 70 to sudden and impulsive strains during replenishment, the jaws are liable to be displaced vertically, and another feature of the present invention, therefore, consists in associating with the bobbin holder a spreader 75 having end portions which overlie the shank and a portion of the bow of the jaws wherein the metal parts are united together as a unit by a through-bolt.

The novel features of the present invention and new combinations of parts will 80 best be made clear from the following description and the accompanying drawings of one good form thereof.

In the drawings:

Fig. 1 is a perspective view of the bobbin holding end of a shuttle with the bobbin holding instrumentalities removed to show more clearly the shank receiving chamber formed in the wood of the shuttle and the reinforcements for the walls of the shank 85 receiving chamber;

Fig. 2 is a view of a bobbin holder and associated parts detached from the shuttle;

Fig. 3 is a plan view showing the parts assembled and held to the shuttle;

Fig. 4 is a longitudinal section on the 95 line 4—4 of Fig. 3; and

Fig. 5 is a transverse section on the line 5—5 of Fig. 3.

The shuttle 1 which is made of wood, as usual, is provided with the usual bobbin holding chamber 2, and towards the end of the shuttle, as indicated in Fig. 1, the wood of the shuttle is cut away to provide an elongated shank receiving chamber 3, the lower wall of which is formed by a table 100 or support 4 comprising a part of the shuttle wood.

The shank receiving chamber 3 extends to

the upper surfaces of the shuttle and is provided with a shoulder or ledge 5, and at the lower terminal portion of the side walls of the shank receiving chamber the shuttle 5 wood is cut away to form the rabbet 6, into which the edge portions of the bottom plate of the guide extend, as will further appear.

The side walls of the elongated shank receiving chamber 3 are reinforced in order to preserve the wood of the shuttle from injury during transfer. In the present instance of the invention, the side walls of the elongated shank receiving chamber are 15 provided with pins 7 which may be conveniently driven into the wood constituting the side walls of the shank receiving chamber, through the shouldered portion 5, as indicated in Fig. 1, the construction being 20 such that when the bobbin holder is laterally expanded by the incoming bobbin, the shank portion thereof which bears against the side walls of the shank receiving chamber will tend to compress the wood of the shuttle 25 constituting such side walls of the shank receiving chamber, and such compressing action will, in accordance with the present invention, be resisted by the reinforcements or pins 7 embedded in the wood of the shuttle chamber. One pin 7, as shown, is in front and the other in rear of the transverse bolt which passes through the shank of the bobbin holder.

Extending through the bottom of the shuttle or table portion 4, as indicated in Figs. 1 and 4, is an opening 8 preferably located at the tip end portion of the shank receiving chamber for the reception of a through-bolt to be described.

40 The bobbin holder indicated in Fig. 2 is provided with the elongated shank portion 9 and bobbin holding jaws 10 which are of the same vertical width as the shank portion 9, and between the bobbin holding jaws 45 10 and the shank portion 9 the bobbin holder is bowed, as indicated at 11, such bowed portion being weakened or recessed in order to distribute and confine the spring action of the bobbin holder to the bowed 50 portion thereof. In the present instance of the invention, the vertical width of the bobbin holding jaws 10 between the points *a*, *b*, is the same as the vertical width of the shank portion between the points *c*, *d*, and 55 between the bobbin holding jaws and the shank portion, the bows 11 are recessed or cut away, as at 12, with the result that while the width of the shank portion and jaws remains the same, the spring action or resiliency of the jaws to permit the incoming bobbin to enter between the jaws, is confined to 60 the bow portion of the bobbin holder. This uniform vertical width of the bobbin holding jaws and the shank, gives strength and 65 stability to the bobbin holder as a whole,

while the weakened or recessed bow portions connecting the jaws and shank, distribute and confine the spring action of the bobbin holder to the bows, without weakening the bobbin holding jaws themselves. When, therefore, the bobbin holding jaws 10 are separated by the incoming bobbin, the resiliency of the bobbin holder is confined 70 to the recessed bows, the outer surfaces of which where they merge into the shank of the bobbin holder bear against the reinforced portion of the shank receiving chamber. 75

It is usual to place between the bobbin holding jaws and the shank of the bobbin holder an inclined bobbin guide for directing the bobbin into holding relation with the jaws on replenishment of filling. In the present instance, the inclined guide is indicated at 13, and at its top is provided with a top plate 14 which overlies the shouldered portion 5 of the shank receiving chamber formed in the wood of the shuttle, and with a bottom plate 15 which rests upon the flush surface of the elongated table or support 4 forming the bottom of the shank receiving chamber. 80 85 90

In accordance with one feature of the present invention, a spacer is provided between the parallel bent portions constituting the shank of the bobbin holder. Such spacer is clearly indicated in Figs. 2 and 4, and comprises end portions which overlie the bobbin holder and with a bent portion 16 which extends downward between the parallel side portions constituting the shank of the bobbin holder, and about or beneath the transverse bolt 17 which passes through the shank of the bobbin holder. 95 100

As indicated in Fig. 4, the front and rear portions of the spacer are disposed between the top of the bobbin holder and the top plate 14 of the bobbin guide, and the tip end portion of the spacer is formed as a plate 18 having an opening 19, the edge portions of the plate 18 being of sufficient size to rest upon the shoulder 5 of the shank receiving chamber. The front end portion of the spacer is provided with wings 20 which overlie the bobbin holder at approximately the point where the bows 11 merge into the shank of the bobbin holder. 105 110 115

Heretofore it has been the usual practice to secure the top plate of the bobbin guide to the shuttle by a screw passing into the wood of the shuttle, a construction which is liable to permit detachment of the parts under the severe strains and shocks to which the shuttle is subjected. In accordance with the present invention, therefore, the metal parts of the bobbin holder and associated elements are held together as a unit by a through-bolt 21 which passes vertically through the top plate 14 of the bobbin guide, the opening 19 of the plate 18 of the 120 125 130

spacer through the shank of the bobbin holder adjacent the end wall 22 thereof, as indicated in Fig. 4, and the lower end of the bolt passes through an opening in the 5 end portion of the bottom plate 15 of the bobbin guide. The lower end of the bolt 21 is threaded, as at 23, and the shuttle wood itself is cut away to form a chamber 24 for the reception of the bolt securing means, 10 such as the nut 25, the construction being such that all the metal parts at the tip end portion of the bobbin holder are united together as a unit by the through-bolt 21, and inasmuch as the end portion 26 of the 15 lower plate of the bobbin guide extends into the rabbets 6, 6, formed in the wood of the shuttle, and the plate 18 and top plate 14 rest upon the shouldered portion 15 of the shank receiving chamber the metal parts are 20 not only clamped together as a unit but are held to the wood of the shuttle (without, however, dependence on the wood of the shuttle) by engagement therewith by the through-bolt.

25 The shank portion of the bobbin holder, as has been heretofore indicated, is elongated and fits the elongated shank receiving chamber of the shuttle, thereby imparting to the bobbin holder as a whole stability of contact 30 with the wooden portion of the shuttle, and such shank portion is substantially longer than the bobbin engaging portion of the jaws 10; and the shank being connected to the bobbin holding jaws by the recessed bows 35 11, to which the spring action of the holder is confined, all liability of breakage of the bobbin holding jaws themselves during transfer is avoided.

What is claimed is:

40 1. An automatically replenishing shuttle having a bobbin holder comprising a shank portion and bobbin holding jaws of equal width, the curved portions of the bobbin holder connecting the shank and bobbin 45 holding jaws and constituting the spring element of the jaws being recessed or reduced in width to distribute and confine the spring of the jaws to the said curved portion, a through-bolt passed vertically through the shank of the bobbin holder, and a trans- 50 verse bolt passing through the shank at right angles to and at one side of the through-bolt.

55 2. An automatically replenishing shuttle provided with a shank receiving chamber of a length greater than the length of the bobbin holding jaws, a bobbin holder comprising a shank portion and bobbin holding jaws of equal width, the shank portion being of a length substantially greater than the bobbin holding jaws to fit the shank receiving chamber, and the curved portion between the shank and bobbin holding jaws being weakened at one edge to distribute and confine 60 the spring of the jaws to said curved por-

tion, and a bolt for securing the shank in the shank receiving chamber.

3. An automatically replenishing shuttle having the wood of the shuttle cut away at one end to form a shank receiving chamber, a bobbin holder comprising shank portion and bobbin holding jaws of equal width with the curved bow portions connecting the two recessed along one edge to confine and distribute the spring of the jaws to said curved portion and avoid breakage of the jaws themselves on replenishment of filling, a through-bolt passed vertically through the shank of the bobbin holder, and a trans- 70 verse bolt passed through the shank of the bobbin holder at substantially right angles to the through-bolt that the bobbin holder may be stabilized in bobbin holding position.

4. An automatically replenishing shuttle having a bobbin holder comprising a shank portion and bobbin holding jaws, a bobbin guide having a top plate and bottom plate, a spreader having a part overlying the shank of the bobbin holder, and a through-bolt 80 passing through the top and bottom plates of the bobbin guide, the spreader, and the shank of the bobbin holder.

5. An automatically replenishing shuttle having a bobbin holder comprising a shank portion and bobbin holding jaws, a bobbin 90 guide having a top plate and bottom plate, a spreader having a part overlying the shank of the bobbin holder, a through bolt passing through the top and bottom plates of the bobbin guide, the spreader, and the shank of the bobbin holder, and a transverse bolt passing through the shank at right angles to the through bolt.

6. An automatically replenishing shuttle provided with a shank receiving chamber, a bobbin holder comprising a shank portion and bobbin holding jaws, the walls of the shank receiving chamber adjacent the shank of the bobbin holder being reinforced to prevent injury to the shuttle wood by the spreading action of the bobbin holding jaws during replenishment of filling, and means for securing the bobbin holder to the shuttle.

7. An automatically replenishing shuttle provided with a shank receiving chamber formed in the wood of the shuttle, a bobbin holder comprising a shank portion and bobbin holding jaws, and a metallic reinforce for the walls of the shank receiving chamber to prevent injury to the wood of the shuttle as the bobbin holding jaws are separated.

8. An automatically replenishing shuttle having an elongated shank receiving chamber, a bobbin holder comprising an elongated shank portion occupying the shank receiving chamber and bobbin holding jaws of the same width vertically as the shank portion and connected thereto by a recessed bow distributing the spring of the jaws to 120 125 130

such recessed bow, and pins for reinforcing the wooden walls of the shank receiving chamber to prevent injury to the shuttle wood as the jaws are spread.

- 5 9. An automatically replenishing shuttle having an elongated shank receiving chamber, a bobbin holder comprising an elongated shank portion occupying the shank receiving chamber and bobbin holding jaws 10 of the same width vertically as the shank portion and connected thereto by a recessed bow distributing the spring of the jaws to such recessed bow, and two bolts passing through the elongated shank portion of the 15 bobbin holder at right angles to each other.
10. An automatically replenishing shuttle having an elongated shank receiving chamber, a bobbin holder comprising an elongated shank portion occupying the shank 20 receiving chamber and bobbin holding jaws of the same vertical width as the shank portion and connected thereto by recessed bows to confine and distribute the spring action of the jaws to such recessed bows, a spreader 25 having front and rear portions overlying the elongated shank of the bobbin holder, and a vertical through-bolt passing through the one of the overlying portions of the spreader and also through the shank portion of the 30 bobbin holding jaws.

11. An automatically replenishing shuttle having an elongated shank receiving cham-

ber, a bobbin holder comprising an elongated shank portion occupying the shank receiving chamber and bobbin holding jaws 35 of the same vertical width as the shank portion and connected thereto by recessed bows to confine and distribute the spring action of the jaws to such recessed bows, a spreader having front and rear portions overlying 40 the elongated shank of the bobbin holder, a vertical through-bolt passing through one of the overlying portions of the spreader and also through the shank portion of the bobbin holding jaws, and a transverse bolt 45 at right angles to the through-bolt passing transversely through the shank portion of the bobbin holder and engaging an intermediate portion of the spreader.

12. An automatically replenishing loom 50 shuttle provided with a shank receiving chamber, a bobbin holder comprising a shank portion and bobbin holding jaws, a transverse bolt for securing the bobbin holder to the shuttle, the walls of the shank receiving chamber having reinforcing pins held in the wood of the shuttle at each side of the bobbin holder shank and nearer the adjacent end of the shuttle than the transverse securing bolt.

In testimony whereof, we have signed our names to this specification.

WALLACE I. STIMPSON.
HARRY A. DAVIS.
